UNITED STATES PATENT OFFICE.

JACOB N. FAUST AND WILLIAM N. EICHBERG, OF CHICAGO, ILLINOIS.

SUSPENDERS.

SPECIFICATION forming part of Letters Patent No. 624,470, dated May 9, 1899.

Application filed May 14, 1898. Serial No. 680,674. (No model.)

To all whom it may concern:

Be it known that we, JACOB N. FAUST and WILLIAM N. EICHBERG, citizens of the United States, residing at Chicago, in the county of Cook and State of Illinois, have invented a new and useful Improvement in Suspenders for Garments, of which the following is a specification.

Our invention relates to suspenders for garments; and our object is to provide means for removing the greater part or all the strain and wear of the ends on the cast-off loops of the webs, which latter form the main body of the suspenders, the same being fully described hereinafter and illustrated in the accompanying drawings, in which—

Figure 1 is a front elevation of the front cast-off loop of one side of a pair of suspenders, showing a double end in position and with the cast-off loop buttoned up in the proper position to hold the end in place. Fig. 2 is an edge elevation of the parts shown in Fig. 1. Fig. 3 is a front elevation similar to what is shown in Fig. 1, but with the cast-off loop unbuttoned and thrown forward and downwardly to the open position, exposing a hook, of metal, in which a single end is suspended. Fig. 4 is the same as Fig. 3, but with a double end in engagement with the hook. Fig. 5 is an edge elevation of the parts shown in Fig. 4, but with the end removed to show hook and the ordinary form of glove-buttoner adapted to hold the cast-off loops of the suspenders in the closed position inclosing the hook, and yet be adapted to be easily opened when it is desired to detach the end from the hook, as is hereinafter more fully shown and described.

Similar letters indicate like parts throughout the several views.

A is the front terminal and adjustable portion of the web of the suspender, which is connected to the cast-off loop B by a link C, as usual, the rivet for fastening the upper end of the cast-off loop B being the fastening-shank portion of the projecting button D of the ordinary form of glove-fastener, whose buttonhole or catch is shown at E. A metal hook F has its upper end portion also secured to the cast-off loop B by virtue of the shank of button D passing through a hole

therein, the hook being clamped between the folded surfaces of the cast-off loop, as shown in Fig. 5.

In Figs. 1 and 4 a double end G is shown, 55 which may have one of its members engaged with the hook F and the other in the cast-off loop B, thus dividing the strain and wear between the hook and loop; but it is obvious that hook F may be made large enough to 60 receive both members G and G' of the end, and thus remove the entire strain from the loop B, which would then serve for the purpose of covering the hook F and for preventing the disengagement of the end therefrom 65 as long as it is buttoned up in the position shown in Figs. 1 and 2.

The ordinary form of single member suspender-end G (shown in Fig. 3) would always be placed in engagement with hook F, from 70 which it may easily be detached by the opening of cast-off loop B.

Any other means may be employed to hold loop B in the closed position in substitution for the glove-buttoner D E without materially 75 altering the intent of this invention.

It is obvious that this device is as well adapted to engage and hold the ends at the back termination of the suspenders as it is for the front cast-off loops.

80

We claim as our invention—

In a suspender for garments, a front cast-off loop comprising a strip having one end attached to the front terminal portion of the web or main body of the suspender, a hook 85 attached to the cast-off strip and adapted to detachably engage with the suspender-ends G G', the free end of the cast-off adapted to swing outwardly and upwardly and fold upon itself, and be detachably secured in the 90 folded position, with the hook within the loop and the suspender-ends in engagement with the hook, in the manner and for the purpose hereinbefore described.

In testimony that we claim the foregoing we 95 have hereunto set our hands, this 28th day of April, 1898, in the presence of two witnesses.

JACOB N. FAUST.

WILLIAM N. EICHBERG.

Witnesses:

EDMUND RISLEY,

ARCHIBALD MCLELLAN.
